(57) **CLAIM**

The ornamental design for a remote control, as shown and described.

DESCRIPTION

FIG. 1 is a front perspective view of a remote control;

FIG. 2 is a front view of the remote control;

FIG. 3 is a rear view of the remote control;

FIG. 4 is a right side view of the remote control;

FIG. 5 is a left side view of the remote control;

FIG. 6 is a top view of the remote control; and,

FIG. 7 is a bottom view of the remote control.

The broken-line disclosure in the views is understood to represent a portion of the article in which the claimed design is embodied, but which forms no part of the claimed design.
